UNITED STATES PATENT OFFICE.

EVERETT J. COOK, OF TOLEDO, OHIO, ASSIGNOR TO THE DURA COMPANY, OF TOLEDO, OHIO, A CORPORATION OF DELAWARE.

WINDOW-CONTROL MECHANISM.

Application filed July 23, 1923. Serial No. 653,266

The invention relates to window control mechanisms and refers particularly to mechanisms for adjusting windows of motor vehicles. One of the objects of the invention is to provide a self-locking window control mechanism in which the control arm is actuated by intermeshing internal and external gears having different numbers of teeth, one gear having an orbital movement relative to the other and having the control arm rigidly secured thereto. Another object is to provide a control mechanism in which the means for counter-balancing the window is a spiral spring connected to the control arm and to the support for the control arm in such a manner that its tension is practically unaffected by the longitudinal movement of the control arm. A further object is the provision of a counter-balancing spiral spring which is normally dished and which when assembled in the control mechanism has its convolutions resting against the support for the control arm whereby rattling is avoided.

With these as well as other objects in view the invention resides in the structural features of construction and arrangements of parts as more fully hereinafter set forth.

In the drawings:

Figure 1 is an interior view of a motor vehicle door equipped with a window control mechanism embodying my invention;

Figure 2 is an enlarged side elevation of the window control mechanism;

Figure 3 is a cross section on the line 3—3 of Figure 2;

Figures 4 and 5 are respectively a side and an edge elevation of the internal gear of the window control mechanism;

Figure 6 is an edge elevation of the counter-balancing spiral spring of the window control mechanism.

1 is a motor vehicle door having in its upper portion a window opening 2 and in its lower portion a chamber 3. 4 is a closure or window in the nature of a glass plate which is slidable in vertical guideways in the door into and from the chamber 3. 5 is the usual lock board extending across the door just below the window opening, and 6 is the liner board also extending across the door but located below the lock board.

7 is a plate secured at its upper and lower edges respectively to the lock board and liner board and forming the support for the window control mechanism. 8 is a bushing ex-

tending transversely of and rigidly secured to the plate, and 9 is a handle shaft extending through the bushing and journaled therein, this handle shaft having secured to its outer end the handle arm 10. 11 and 12 are respectively the internal and external gears for effecting the driving connection between the handle shaft 9 and the window control arm 13, which latter has the roller 14 at its free or outer end operatively connected to the window 4.

The gears 11 and 12 have different numbers of teeth and one has a bodily orbital movement relative to the other to effect the swinging of the control arm. As shown, the internal gear 11 is rigidly secured to the supporting plate 7 while the external gear 12 is rotatably mounted upon the eccentric 15 fixed upon the inner end of the handle shaft 9, the eccentricity of the eccentric being equal to one-half the difference in pitch diameters of the gears so that the latter are in mesh at all times, and when the handle shaft is rotated the points of engagement of their teeth rotate with the eccentric. The control arm 13 is also rotatably mounted upon the eccentric 15, but it is secured to the external gear 12 by means of the rivets 16. With this arrangement, rotation of the handle shaft effects a bodily orbital movement of the external gear 12 to bring the teeth of the same successively into mesh with the teeth of the internal gear, thereby effecting a rotation of the external gear upon the eccentric. Since the control arm is rigidly secured to the external gear, the same will be swung to raise or lower the window.

17 is a window counter-balancing spring of spiral form having its inner end connected to the supporting plate, and its outer end to the control arm. By reason of this arrangement, the longitudinal movement of the control arm caused by it being mounted upon the eccentric does not appreciably affect the tension of the counter-balancing means, and as a consequence, the raising and lowering of the window is more uniform. Apparently this is due to the fact that the longitudinal movement of the control arm effects a radial movement of the end of the spiral spring connected thereto which varies the circumferential length of the coil spring but very slightly so that its tension remains practically the same. Still another point is that the spiral spring is so made and assembled that its convolutions

do not engage each other at any time and as a consequence do not offer any frictional resistance by being wrapped upon each other.

For the purpose of providing a window control mechanism in which the same parts may be used upon either a right hand or a left hand door, the spiral spring has its opposite ends hooked with the return bent portions in the plane of the spring. Also, the means for securing these hooked ends to the supporting plate and control arm extend into the plane of the spring. As shown the control arm 13 extends beyond the eccentric 15 and has the transverse flange 18 at its end, the edge of which is engaged by the outer hooked end of the spiral spring, the portion of the outer convolution adjacent this hooked end lying over the transverse flange. The internal gear 11 forms the connection between the inner hooked end of the spiral spring and the supporting plate. This internal gear as shown in Figures 4 and 5 particularly has the peripheral spaced transversely extending ears 19 provided with shoulders 20 and tongues 21, the latter extending through openings in the supporting plate and being riveted thereover with the shoulders 20 against the inner side of the plate. The tongues are of such a length that the inner hooked end of the spiral spring may enter between the supporting plate and body of the internal gear and engage an edge of one of the ears. Owing to the fact that a number of ears are provided that are engageable with the inner hooked end of the spiral spring, the tension of the spring may be readily varied. With this arrangement, if it is desired to convert the window control mechanism so that it may be assembled in a right hand door instead of a left hand door, the spiral spring may be removed and reversed, at which time its hooked edges will engage the opposite edges of the transverse flange 18 upon the control arm and of one of the ears 19 upon the internal gear.

To avoid rattling occasioned by the transverse movement of the convolutions of the spiral spring, I make my spiral spring as shown in Figure 6 particularly of dished form so that when assembled in the window control mechanism and its convolutions are

forced into the same plane they will exert pressure at all times upon the supporting plate 7.

From the above description it will be readily seen that I have provided a simple construction of self-locking window control mechanism in which the internal gear and also the external gear and control arm as well as supporting plate may be formed of stampings. It will also be seen that I have provided a window counter-balancing means which is practically unaffected by the longitudinal movement of the control arm. Furthermore, that this window counter-balancing means may be readily changed to be incorporated into a window control mechanism for either a right hand or left hand door. Still other features of my invention are evident, namely, the connecting of the spiral spring forming the window counter-balancing means to the supporting plate by means of the riveting portions of the internal gear secured to the supporting plate, and the dishing of the spiral spring so that its convolutions will bear against the supporting plate to avoid rattling.

What I claim as my invention is:

1. In a window control mechanism, the combination with a support, of a control arm mounted upon said support, and a spiral counter-balancing spring connected to said support and arm, said spring having its convolutions tensioned to bear against one of said members.

2. In a window control mechanism, the combination with a supporting plate, of a swinging control arm carried by said plate, and a spiral normally dished counter-balancing spring connected to said plate and arm having each of its convolutions bearing resiliently against one of said members.

3. In a window control mechanism, the combination with a supporting plate, of a control arm carried by said plate, means for effecting a combined oscillatory and swinging movement of said arm, and a spiral normally dished counter-balancing spring having its convolutions bearing against one of said members.

In testimony whereof I affix my signature.

EVERETT J. COOK.
